UNITED STATES PATENT OFFICE.

LUCIUS M. BEDELL, OF CHETOPA, KANSAS.

BARREL-TRUCK.

SPECIFICATION forming part of Letters Patent No. 274,258, dated March 20, 1883.

Application filed January 3, 1883. (No model.)

To all whom it may concern:

Be it known that I, LUCIUS MELVIN BEDELL, a citizen of the United States of America, residing at Chetopa, in the county of Labette and State of Kansas, have invented a new and useful Improvement in Barrel-Trucks, of which the following is a specification, to wit:

This invention relates to improvements in barrel-trucks; and it consists in a square or angular frame set upon small wheels and provided with an adjustable retaining-arm having a suitable handle, substantially as hereinafter more fully described.

In order to enable others skilled in the art to which my invention belongs to avail themselves of its benefits, I will now proceed to describe it, referring to the accompanying drawings, in which—

Figure 1 is a perspective view of my truck with a barrel shown upon it in dotted lines, and Fig. 2 a vertical cross-section of the same.

A represents a square or angular frame, of wood, having its ends mortised, as shown, and provided on two or more corners with triangular blocks *a a*. This frame is provided also with four or more small wheels, *a'*, which are secured in slots in the frame and project somewhat beneath it, as seen in the drawings. On its forward side the frame A is provided with an L-shaped arm, B, having its short or horizontal arm furnished with a series of holes,

b, by which it may be adjustably secured to the frame. The perpendicular portion of this arm B is supplied with a handle, *b'*, which may be made removable, if so desired.

In use a barrel or box is placed upon the truck or frame A, with its edges resting against the corner-pieces *a* to prevent its slipping or being upset. The arm B is secured to the box; or in case of a barrel may be passed under its upper hoops and holds it firmly in place, while it may be readily moved around or drawn out or pushed beneath a counter by means of the handle *b'*. The arm B, being adjustable upon the frame, is easily thrown out or in to suit boxes or barrels of different sizes.

Having thus fully described my invention, what I claim as new, and desire to secure by Letters Patent, is—

In a barrel-truck, the combination of a square or angular frame provided with slots in which are small wheels or rollers, and two or more corner-pieces, with an L-shaped arm, adjustably secured to the frame and provided with a handle, substantially as and for the purpose set forth.

In testimony whereof I affix my signature in presence of two witnesses.

LUCIUS MELVIN BEDELL.
